UNITED STATES PATENT OFFICE.

JAMES A. MUZZIO, OF CLEVELAND, OHIO, ASSIGNOR TO ROSA S. MUZZIO, OF CLEVELAND, OHIO.

LOCKING MECHANISM.

Application filed January 2, 1923. Serial No. 610,202.

This invention relates to locking mechanism and particularly to such mechanism embodying a locking device of the cylinder type.

5 The objects of the invention are to provide improved mechanism or means actuated by the cylinder lock for throwing the bolt or other locking member, said mechanism or means being adapted for actuation by the 10 plug of a cylinder lock in which the plug is concentric with the cylinder, the arrangement being such that said mechanism or means can be entirely retracted within the cylinder to enable it to be screwed into the lock.

15 A further object of the invention is to provide locking mechanism of the kind described in which the bolt actuating mechanism has a quick throw with limited movement of the key so that the locking bolt can be fully thrown with relatively small key 20 movement.

Other objects of the invention are in part obvious and in part will appear more in detail hereinafter.

25 In the drawings, Fig. 1 represents a sectional elevation on the line 1—1, Fig. 3, through a supporting body provided with my improved locking mechanism, the casing plate being omitted to expose interior parts 30 and the locking bolt being shown in released or unlocked position; Fig. 2 is a similar view showing the parts in locked position; Fig. 3 is a sectional elevation on the line 3—3, Fig. 2; Fig. 4 is a perspective view 35 of the inner end of the cylinder lock; and Fig. 5 is a detail section on the line 5—5, Fig. 3.

40 My invention contemplates the organization of a cylinder lock, such as shown in Fig. 4, with any suitable lock including a movable locking bolt or the like actuated by the cylinder lock, such organization being shown in Fig. 1. The cylinder lock is of special form in that it comprises a relatively stationary cylinder member 1 non-rotatably secured to the door or other part 2 to which the lock is secured, such as by the usual holding screw 3, and in which cylinder member is a rotatable plug 4 actuated by the key 5. Said 45 plug is concentric with the cylinder 1 instead of being eccentric thereto as in most forms of cylinder locks. The key actuated interlocking devices between the cylinder and plug may, of course, be of any suitable description and may be either pins, levers or

any other like devices, and, for example, may be of the same construction and arrangement as illustrated in my prior application for cylinder lock, filed January 13, 1922, Serial No. 528,952, to which reference 60 may be had for a more complete description thereof if required. The cylinder 1 is screwed through an opening 6 in the door 2 into a threaded opening in the casing 7, which is provided with the usual removable 65 plate or cover 8. In said casing are located the locking bolt and other cooperating parts which may be of any suitable description. The drawings show for this purpose a slideable locking bolt 9 on which is pivoted a 70 spring actuated lever 10 having a hook portion 11 working between the two bevelled stops 12 on the bolt, said lever being pivoted to the bolt 9 and having a projection 13 cooperating with the stationary stop or abutment 14, all as usual. The locking bolt is thrown by a member operated by the rotatable plug 4 and which in its movement to and fro enters the recess between the two stops 12, engages the end of the hook member 11 and pushes the same back, and then by engagement with one or the other of the bolt stops 12 produces sliding motion of the bolt, after which the lever 10 is returned by its spring 15 to latching position. 80

To effect operative connection between the rotating plug 4 and the movable bolt 9, the cylinder lock of the present invention is provided with mechanism as follows:

85 On the inner end of the cylinder member 1 is a stationary ring 16 which may be integral with the cylinder but is shown as held thereto by screws 17, and on which is pivotally mounted at 18 a lever 19 having an elongated slot 20 therein. Within the opening in the ring 16 is rotatably mounted the disc shaped base 21 of a crank arm 22, said arm having an opening 23 through which to insert a screw driver or other implement for attaching said crank arm to the end of the plug 4 90 by the screw 24. Said plug and the crank arm rotate together and are held against relative rotation by wings or ears 25 on the plug entering recesses in the base of the crank arm. Said crank arm, eccentrically to the plug, is provided with a pin or crank 95 26 entering the slot 20 in lever 19.

100 After the lock casing 7 with its contained parts is mortised into the door and secured in place such as by the screws 30 the cylinder 110

der lock, with its crank arm and lever turned to the position shown in Fig. 1 is screwed into the lock casing until the parts reach the position shown in Figs. 1 and 3, whereupon the holding screw 3 is turned up to enter the usual longitudinal groove 31 in the cylinder 1. With the parts in the positions shown in Fig. 1, both the crank arm 22 and all parts of lever 19 are within the cylindrical boundary of the cylinder 1. If the key 5 is now turned so as to produce rotation of the plug in the counter clockwise direction, Fig. 1, crank arm 22 also turns in the counter clockwise direction and its pin 26 travels along the slot in lever 19 and causes the same to turn about its pivot so that its outer end enters the recess between stops 12 and pushes back the lever 10 to the position shown in Fig. 2. Continued motion completes the throwing movement of the locking bolt and again withdraws lever 19 within the limits of the cylinder on the opposite side of its eccentric, as will be readily understood. Reverse motion unlatches the bolt and then moves it back to unlocked position.

With this arrangement full locking or unlocking movement requires approximately 180° rotation of the key, instead of 360°, as is usually the case, although if desired, the key can be given more movement for the locking effect. Again, the arrangement enables the cylinder and plug to be concentric with each other, thus reducing the required size of the cylinder, so that the cylinder mechanism as a whole may be reduced in size. As the pin 26 on the crank arm travels through its orbit, it approaches nearer and nearer the pivot 18 so that when lever 19 is effecting the locking or unlocking movement the multiplication of travel is a maximum. The locking movement is therefore accomplished with a quick snapping action calculated to over-ride slight obstructions, as where the parts do not work efficiently or are inaccurately made.

Further advantages of the invention will be apparent to those skilled in the art.

What I claim is:

50. 1. Cylinder locking mechanism, compris-

ing relatively rotatable concentrically disposed cylinder and plug members, an operating crank arm rotatable with the plug and spaced endwise therefrom and having a crank pin extending toward the plug, a slotted bolt operating lever pivoted on the cylinder member and lying in the space between said crank arm and plug, the slot of said lever receiving said crank pin, whereby said arm may be removed from the plug without disturbing said lever.

2. Cylinder locking mechanism, comprising relatively rotatable concentrically disposed cylinder and plug members, a slotted bolt operating lever pivoted on the cylinder member on an axis eccentric to the cylinder axis, and an operating arm therefor rotatable with the plug and having a crank pin working in said slot, said pin being radially more remote from the plug axis than the axis of rotation of said lever.

3. Cylinder locking mechanism, comprising relatively rotatable concentrically disposed cylinder and plug members, said cylinder member having an annular end portion, a crank arm having a base extending through the opening in said annular end portion and secured to rotate with the plug, a bolt-throwing lever pivoted to the cylinder and lying between the end of the cylinder and said arm, and inter-engaging operating connections between said arm and lever.

4. Cylinder locking mechanism, comprising relatively rotatable concentrically disposed cylinder and plug members, said cylinder member having an annular end portion, a crank arm having a base extending through the opening in said annular end portion, a securing device extending through the base and into the plug for securing said arm thereto, said arm having an opening providing access to said device, a bolt-throwing lever pivoted to the cylinder and lying between said cylinder and said arm, and inter-engaging operating connections between said arm and lever.

In testimony whereof I hereby affix my signature.

JAMES A. MUZZIO.
